UNITED STATES PATENT OFFICE.

HENRY W. PAINE, OF EAGLE GROVE, IOWA.

LIFTING-TOOL FOR EXPLOSION-ENGINE-VALVE ROCKER-ARMS.

1,357,817.

Specification of Letters Patent.

Patented Nov. 2, 1920.

Application filed February 28, 1919. Serial No. 279,711.

To all whom it may concern:

Be it known that I, HENRY W. PAINE, a citizen of the United States, residing at Eagle Grove, in the county of Wright, and 5 State of Iowa, have invented a new and useful Lifting-Tool for Explosion-Engine-Valve Rocker-Arms, of which the following is a specification.

This invention has reference to lifting 10 tools for explosion engine valve rocker arms, and its object is to provide a tool by means of which the valve springs of certain types of explosion engines can be easily compressed, thus freeing the valve from the lifting rod and allowing the outer end of the 15 rocker arm to be dropped down preparatory to removing the valve from the motor.

The invention is designed particularly for use in connection with the engine of an automobile known in the trade as the Buick 20 automobile, but may also be used with other types of valve-in-the-head motors.

In the type of motors referred to the valve 25 springs are compressed, in the operation of the motor, by a rocker arm actuated by a lifter rod. When it is desirable to remove a valve the rocker arm must be tipped to a greater extent than usual in order to release it from the lifter rod, thereby demanding 30 a compression of the valve spring to a corresponding extent. These operations have usually heretofore been done by prying the rocker arm with a screw-driver or some other ordinary tool, such as a wrench or a 35 pair of pliers, but as the valve springs are very stiff such methods of compressing the springs are unsatisfactory, slow and at times quite difficult.

The invention comprises a tool shaped to 40 grasp the rocker arm in a manner giving ample leverage to compress the spring and thereby lift the other end of the rocker arm to an extent permitting its disengagement from the lifter rod, and then the valve may 45 be easily removed for repairs, grinding or replacement.

The Buick automobile differs, in the 50 rocker arm construction, in the more recent models from earlier ones, this requiring some differences in the parts of the rocker 55 arm lifting tool so that such tool may be used, especially in garages and repair shops for different types of machines upon which work must be done, and the invention provides a tool of correspondingly wide use.

The invention will be best understood

from a consideration of the following detailed description taken in connection with the accompanying drawing forming part of this specification, with the understanding, 60 however, that the invention is not confined to any strict conformity with the showing of the drawing, but may be changed and modified so long as such changes and modifications mark no material departure from the 65 salient features of the invention as expressed in the appended claim.

In the drawing:—

Figure 1 is an elevation showing the application of the tool of the invention to a 70 Buick rocker arm of earlier models.

Fig. 2 is a similar view of the tool applied to a Buick rocker arm of the most recent model.

Fig. 3 is a perspective view of the tool. 75

Fig. 4 is an elevation of one end of the tool.

Referring to the drawing, there is shown in Fig. 1 a rocker arm 1, valve stem 2, valve spring 3, lifter rod 4, and support 5 for the 80 rocker arm, as used in the 1918 and earlier models of the Buick automobile. In Fig. 2 there is shown a rocker arm 1^a, valve stem 2, spring 3, lifter rod 4 and support 5 for the rocker arm, as these parts are made in the 85 1919 model of the Buick automobile.

The tool, which is best shown in Fig. 3, comprises a bar 6, which may be made of flat bar steel, of, say, quarter inch gage and about an inch wide and nine or ten inches 90 long, although these particular dimensions are by no means obligatory. One end of the bar has a continuation in the form of a bend 7 at an obtuse angle to the length of the bar and this bend terminates in a fork 8 projecting laterally from the angular portion 7. The fork 8 projects at an obtuse angle to the continuation 7 and makes about a right angle continuation of the bar 6. The fork 8 has curved or bowed legs approaching at 100 their free ends. The other end of the bar 6 is formed into two spaced and substantially parallel legs 9 in actual or approximate alinement with the length of the bar 6.

The rocker arm 1 or 1^a has at the end 105 remote from that engaging the valve stem 2, a head or enlargement 10 in which there is a socket for a ball projection 11 on the lifter rod 4. In the earlier models of the rocker arm, as shown in Fig. 1, the bar 6 is employed as a lever extension from the ball-receiving socket-end of the rocker arm 1,

said bar being applied to one side thereof with the fork 8 straddling the rocker arm 1 adjacent to the socket enlargement 10 and with the other end of the bar 6 extending 5 away from the spring-engaging end of the rocker arm, thus materially prolonging that end of the rocker arm remote from the spring. The bend 7 and the approaching 10 curve of the legs of the fork 8 aid in safely holding the bar 6 in gripping engagement with the rocker arm. Now, on lifting that end of the bar 6 provided with the legs 9, the spring 3 is readily compressed because 15 of the relatively great leverage provided. The socket end of the arm 1 is lifted high enough to release the ball end 11 of the lifter rod 4, so that the latter may be moved out of the way and the rocker arm 1 is then free to fully release the spring. The valve 20 may then be removed and reinserted or replaced by a new one, whereupon, the arm 11 may be moved by the bar 6 as a handle to an extent compressing the spring 3 so that the lifter rod 4 may be properly replaced. 25 The normal position of the parts is shown in full lines in Fig. 1 and the position of the parts when the lifting tool has been operated to compress the spring as shown in dotted lines.

30 Because of conditions present in the latest model, the use of the lifting tool applied, as shown in Fig. 1, is not feasible, so the end of the tool having the legs 9 is applied to the arm 1^a in a manner to straddle the latter 35 and engage the socket enlargement 10 with the fork 8 then remote from the arm engaging part of the tool. This provides long leverage ample to compress the valve spring, but with the tool oppositely related to the 40 rocker arm from the arrangement shown in Fig. 1. Both the inactive and the active positions of the tool 6 when used on the

latest model of the automobile engine are indicated in full and dotted lines in Fig. 2.

By providing in a single tool means for 45 operating upon different models of the type of automobile engine for which the tool is intended, the cost of the tool is cheapened and its usefulness is greatly enhanced, although the prime purpose of the tool is the same with respect to both ends thereof, that is, to compress the valve springs of valve-in-the-head automobile engines in which the valves are operated by lifting rods through the intermediary of rocker arms. 50

55 The fork 8 of the bar 6 is made C-shape with the legs shaped similar to the showing of the drawing, or otherwise, to prevent the tool from slipping off the rocker arm. A slight curvature of one of the legs of the 60 fork 8 aids materially in this respect.

The continuation or bend 7 has the advantage of permitting the bar 6 to lie flat against the ball receiving end 10 of the rocker arm thus bringing the body of the 65 tool practically parallel with the arm 1 and overcoming any tendency of the tool to turn around on the rocker arm instead of lifting it.

70 What is claimed is:—

A rocker arm lifting tool for automobiles, comprising an elongated bar with one end bent at an obtuse angle and terminating in a fork at substantially right angles to the length of the bar and having the legs of the 75 fork shaped to embrace and grip the rocker arm.

In testimony that I claim the foregoing as my own, I have hereto affixed my signature.

HENRY W. PAINE.
